UNITED STATES PATENT OFFICE.

OSCAR LINDEMANN, OF TOMPKINSVILLE, NEW YORK.

DESIGN FOR A BIRDCAGE.

Application filed December 28, 1925. Serial No. 15,876. Term of patent 7 years.

To all whom it may concern:

Be it known that I, OSCAR LINDEMANN, a citizen of the United States, residing in Tompkinsville, in the county of Richmond and State of New York, have invented a new, original, and ornamental Design for Birdeage, of which the following is a specification, reference being made to the accompanying drawing, forming part thereof, in which the figure in the drawing represents a perspective view of a birdcage showing my new design.

I claim:

The ornamental design for a birdcage as shown.

OSCAR LINDEMANN.
